Patented Feb. 12, 1918.

Inventor:

Earl O. J. Danielson

By his attorney Wiley J. Gooding

UNITED STATES PATENT OFFICE.

EMIL O. J. DANIELSON, OF BOSTON, MASSACHUSETTS.

DESIGN FOR A FLAG-POLE.

51,751.

Specification for Design.

Patented Feb. 12, 1918.

Application filed March 7, 1917. Serial No. 153,208. Term of patent 3½ years.

To all whom it may concern:

Be it known that I, EMIL O. J. DANIELSON, a citizen of the United States, residing at Boston, in the county of Suffolk and State of Massachusetts, have invented a certain new, original, and ornamental Design for a Flag-Pole, of which the following is a specification, reference being had to the accompanying drawing, forming part thereof.

The figure is a front elevation of a flag pole, showing my new design.

I claim:

The ornamental design for a flag pole, as shown.

In testimony whereof I have hereunto set my hand in presence of two subscribing witnesses.

EMIL O. J. DANIELSON.

Witnesses:

CHARLES S. GOODING,
SYDNEY E. TAFT.
